Primary Examiner — Selina Sikder

(57) **CLAIM**

The ornamental design for an electrical switch as shown and described.

DESCRIPTION

1. Electrical switch

2. Electrical switch

The figures show electrical switches.

Fig. 1.1 is a front view

Fig. 1.2 is a first side elevation view

Fig. 1.3 is a second side elevation view

Fig. 1.4 is a top view

Fig. 1.5 is a bottom view

Fig. 1.6 is a rear view

Fig. 1.7 is a perspective view

Fig. 2.1 is a front view

Fig. 2.2 is a first side elevation view

Fig. 2.3 is a second side elevation view

Fig. 2.4 is a top view

Fig. 2.5 is a bottom view

Fig. 2.6 is a rear view

Fig. 2.7 is a perspective view

The broken lines showing portions of the electrical switch are for illustrative purposes and forms no part of the claimed design.

1 Claim, 14 Drawing Sheets
